MAGNETIC MEANS FOR STIRRING
MERCURY IN AN IGNITRON

Joseph Slepian, Pittsburgh, and William E. Pakala, Forest Hills, Pa., assignors to Westinghouse Electric & Manufacturing Company, East Pittsburgh, Pa., a corporation of Pennsylvania

Application July 9, 1938, Serial No. 218,354

7 Claims. (Cl. 250—27.5)

Our invention relates to a vapor electric device and more particularly to means for stirring the liquid cathode generally used in such devices.

In the operation of vapor electric discharge devices of the type utilizing a liquid pool cathode, such as a mercury pool, a considerable amount of heat is set free at the cathode spot terminal of the electric arc. Due to the low coefficient of thermal conductivity of mercury, this heat cannot escape readily by conduction through the mercury to the cooling surfaces and as a result the surface of the mercury attains a high temperature. The effect is somewhat mitigated by the stirring of the mercury with the accompanying convective transfer of heat caused by the fluctuating pressure of the cathode. In actual devices, a surface temperature of nearly 100° C. may be reached over most of the mercury surface. With such temperatures, the rate of vaporization is high, leading to a high vapor density in the device with frequent arc-backs occurring.

According to our invention, we provide a means for stirring the mercury cathode vigorously and directing it in paths along cooling surfaces. Briefly, we submerge magnetic devices in the mercury in such a position that magnetic fields are set up which react with the electric currents in the mercury thus producing motion of the mercury. More particularly, we submerge permanent magnets, preferably of the horseshoe type, in the mercury, thus creating a number of strong magnetic fields therein. Moreover, we may mount a guide of some non-conducting material, such as a quartz block, in the mercury just below the tip of the make-alive electrode in case such an electrode is used to direct the flow of current which is being conducted by the mercury. When the current which is flowing into the mercury crosses the magnetic fields, a sidewise force is imparted to the mercury according to well known principles of electromagnetism and a number of whirls are established. By positioning a cooling coil in the mercury along the whirling paths, the mercury is moved therewith and cooled.

It is, therefore, an object of our invention to provide means for stirring the liquid metallic cathode in a vapor electric device. Another object of our invention is to provide a means for preventing the formation of an excessive amount of metallic vapor in an electric discharge device, thereby increasing the capacity of such devices.

Still further, it is an object of our invention to provide means for minimizing the wide fluctua-

tions in the temperature gradient along various points of the mercury surface.

Another object of our invention is to provide means for more effectively cooling the mercury cathode of a vapor discharge device.

Other objects and advantages of our invention will be apparent from the following detailed description taken in conjunction with the accompanying drawing, in which:

Figure 1 is a sectional elevation of a vapor electric discharge device employing magnets for stirring the mercury cathode showing a view taken along the lines I—I of Fig. 2, and

Fig. 2 is a sectional view of the mercury cathode illustrating the location of the magnets and cooling coils and the paths assumed by the mercury when a reaction of the magnetic field upon the current in the mercury takes place.

Referring more particularly to Figure 1, we illustrate a vapor electric converter 3 comprising an evacuated container 5, an anode 7 and a cathode 9 commonly comprising mercury in the lower portion of the container 5. Submerged within the cathode 9 are a plurality of permanent magnets 11 preferably of the horseshoe type for setting up a number of magnetic fields therein. The magnets 11 may be either of the permanent type or of the temporary type, such as electromagnets. It is to be understood, however, that while we have shown a specific type of magnet 11, we do not wish to limit ourselves thereby to any one design or class of magnets 11. Preferably, the magnets 11 are insulated from the mercury cathode 9 by completely covering them with some insulating coating (not shown) such as a vitreous enamel and supporting them by supporting legs 12 secured to the base of the container 5. Each of the magnets 11 has a notch 13 or groove in the yoke portion 15 to afford a passageway for the flow of mercury, as we shall hereinafter describe more fully. In mounting the magnets 11 in place, we prefer to arrange the magnets 11 so as to have unlike poles of adjacent magnets 11 together, thereby being able to ascertain the direction of the lines of force of the magnetic field.

In contact with the mercury cathode 9 and slightly projecting below its surface, we have provided a make-alive electrode 17 composed of some resistance material such as boron carbide or carborundum. This electrode 17 is held in position by a depending portion of a rigid conductor 19 secured to but insulated from the container wall 5.

In a central portion of the mercury cathode 9

and located below the make-alive electrode 17, we have provided a suitable guide 21 made of some non-conducting material such as a quartz block to direct the flow of current conducted by the 5 mercury towards the magnetic fields surrounding the horseshoe magnets 11. The guide 21 may be supported by providing a plurality of supporting legs 22 fastened to the container 5. It is to be understood, however, that the tip of 10 make-alive electrode 17 need not be in contact with the guiding element 21 as such an arrangement serves no useful purpose.

Referring to Fig. 2, we have provided a cooling coil 23 which may be mounted radially, spirally 15 or otherwise in the mercury cathode 9. In order to obtain a more rapid heat transfer from the hottest point in the mercury cathode 9 to the cooling coil 23, we prefer to use a coil 23 formed of material having a high coefficient of heat conductivity such as copper, the exterior surface 20 of which may be coated with a suitable non-amalgamable material such as a nickel plating. Preferably, we wish to locate various portions of the cooling coil 23 in such positions that the mercury, when stirred, will be in close proximity to the coil 23. The cooling medium used may be fresh water and is admitted into the coil 23 through an inlet valve 25 which may be used to regulate the flow of water.

30 In the operation of our device 3, a suitable current is permitted to flow through the make-alive electrode 17 whereupon a cathode spot is produced at the junction of the make-alive electrode 17 and the cathode material 9 and under proper 35 conditions of potential, the cathode spot expands into an arc, which immediately transfers to the anode 7 and the rectifying process has begun. In accordance with the accepted convention of current flow, the rectified current is considered as flowing from the anode 7 to the cathode 9 and thence through the cathode lead 27. However, 40 the guiding element 21 which is centrally mounted in the mercury cathode 9 directs the current being conducted by the mercury into the magnetic fields set up by the magnets 11. In order to determine the direction of motion of the mercury, the application of the familiar left-hand rule for motors which states that when a conductor carrying a current, which in our case is 45 mercury, is placed in a magnetic field, a sidewise thrust is imparted. As a result of such motor action of the field upon the current in the mercury, a plurality of whirls 29 are established in the mercury cathode 9 and according to observations in the laboratory where four magnets 11 are used, eight such whirls 29 were created.

Although we have shown and described a certain specific embodiment of our invention, it is apparent that changes and modifications may be made therein without departing from the spirit and scope of our invention. We desire, therefore, that only such limitations shall be imposed as are embodied in the accompanying claims or as may be necessitated by the prior art.

46 We claim as our invention:

1. In an electrical discharge device comprising

5 a plurality of principal electrodes at least one of which is a liquid metallic cathode, means disposed in said cathode for setting up a magnetic field, means for establishing a current in said cathode and means centrally disposed in said cathode for directing the current in said cathode into said magnetic field.

2. In an electrical discharge device comprising a liquid metallic cathode, means submerged in said cathode for establishing magnetic fields, 10 guiding means directing the current in said cathode so as to be subjected to the influence of said magnetic fields.

3. An electric discharge device comprising a liquid metallic cathode, a plurality of permanent 15 magnets submerged in said cathode, an insulating covering on each of said magnets, a guide of non-conducting material for directing the current into magnetic fields set up by said magnets whereby a plurality of whirls are set up in said cathode. 20

4. In an electric discharge device comprising an evacuated container, a liquid metal cathode in said container, an auxiliary electrode in contact with said cathode in a central portion thereof for initiating a cathode spot, a plurality of 25 permanent magnets submerged in said cathode, said magnets having their pole pieces in the neighborhood of said cathode spot, the magnetic fields set up by said magnets moving portions of said liquid cathode adjacent said cathode spot 30 towards the walls of said container when said cathode is carrying current.

5. An electric discharge device comprising a plurality of principal electrodes at least one of which is liquid, an auxiliary electrode in contact 35 with and centrally disposed in said liquid, a plurality of permanent magnets submerged in said liquid electrode, means for establishing a current in said liquid, a non-conducting guiding element for directing the current in said liquid electrode 40 into magnetic fields set up by said magnets, said guiding element centrally disposed in said liquid electrode but spaced from said auxiliary electrode.

6. In an electric discharge device comprising a liquid metallic cathode, an auxiliary electrode 45 having a tip portion in contact with and centrally disposed in said cathode, a block of non-conducting material beneath said tip portion of said auxiliary electrode but spaced therefrom, magnetic means for setting up a plurality of magnetic fields in said cathode, said magnetic fields 50 subjecting said liquid cathode into a plurality of whirling movements when said liquid cathode is carrying current and cooling means arranged within said cathode as to be substantially in parallel with said whirling cathode.

7. Apparatus for stirring mercury in a vapor electric converter comprising in combination a plurality of permanent magnets uniformly disposed in said mercury and a guiding element of non-conducting material for influencing the path of said mercury when conducting a current into electric fields set up by said magnets whereby said mercury is subjected to whirling movements.

JOSEPH SLEPIAN.
